UNITED STATES PATENT OFFICE.

JOHN A. PILCHER, OF ROANOKE, VIRGINIA.

LOCOMOTIVE-TENDER-TANK FEEDER.

1,241,439.

Specification of Letters Patent. Patented Sept. 25, 1917.

Application filed October 17, 1914. Serial No. 867,131.

To all whom it may concern:

Be it known that I, JOHN A. PILCHER, a citizen of the United States, residing at Roanoke, in the county of Roanoke and State of Virginia, have invented certain new and useful Improvements in Locomotive-Tender-Tank Feeders, of which the following is a specification.

This invention relates to locomotive tender tank feeders or to means for filling railway tanks with water while under way, and its object is to provide improvements over the devices now used for this purpose.

It is customary at the present time to provide a long shallow tank of rectangular cross section in the track, between the rails, for holding a supply of water, and a scoop is then let down by one of the enginemen and the impetus of the scoop against the water drives it up the scoop and discharges it into the tender tank.

With such devices it is necessary that the locomotive or tender be traveling at considerable speed, inasmuch as the water must rise to a height of about ten feet in order to be discharged into the tender tank. Also, with the track tank so placed there is trouble with flying ballast and dirt getting into the track tank and then into the tender tank.

Furthermore, the placing of the track tank on the wooden ties hastens their decay and at the same time makes their replacement difficult. A still further disadvantage is the difficulty of detecting leaks in the track tank and the tendency of the vibrations and sinking of the track is to break the track tank joints and cause leaks, particularly with the rectangular shaped tank which must necessarily be used because of lack of space for my semi-circular tank.

In the present invention the track tank is elevated along side of the track and these difficulties are avoided. My invention also provides substantial and convenient means for transferring the water from this elevated tank to the tender tank, and in addition I am enabled by locating the track tank to the side of the track to make it of semi-circular cross section which not only is more easily manufactured, but is also more easily maintained, presents a more efficient surface and clearance for the scoop and is a stronger and stiffer tank mechanically.

My invention also provides a new and improved method of projecting and withdraw-

ing the water scoop from the tender and I have further provided a simple and desirable means for preventing the scoop striking the end of the track tank in case it should be projected too early or not withdrawn at the proper time.

With these objects, therefore, and others in view, the invention consists in the construction and in the combination of elements as herein described and claimed.

In the drawings, Figure 1 represents an end elevation, partly in section, of a tender having a portion of my invention applied thereto and having the track tank of my invention shown in its relative position.

Fig. 2 is a partial side elevation of the water scoop as used, showing the portion that is let down into the water in the track tank.

Fig. 3 is a partial plan view of the tender and mechanism of Fig. 1, the same showing also in plan view the track tank.

Fig. 4 shows an alternate arrangement of the water scoop of my invention, the same being shown applied to a tender and the view being a view similar to Fig. 1.

Fig. 5 is a side elevation of a portion of track with a tender thereon, along side of the track tank of my invention, this figure being drawn to a reduced scale.

Fig. 6 is a partial plan view of a tender showing the means for closing the end of my water scoop against the entering of cinders.

Referring now to the drawings wherein like parts are similarly designated, 1 represents a locomotive tender on the track 2. To one side of this track and removed a suitable distance therefrom is a track tank 3 which extends continuously for a proper distance along the track.

This track tank 3 is elevated to a position near the top of the tender and is shown as supported on structural steel bents 4 which in turn are placed on concrete piers 5. The tank 3 is made substantially semi-circular in cross section, this form being economical of construction and serving better to provide a minimum amount of clearance for the rocking that will obtain when the scoop is affixed to the top of the tender. It also possesses other advantages over other sections as hereinbefore cited.

The scoop 6 of my invention is made in form of a portion of a hollow cylindrical ring when viewed in end elevation of the

tender and it follows the path of a circular arc in being projected into or withdrawn from the track tank 3. In cross section, as stated, this water scoop is made preferably 5 circular inasmuch as in addition to being easy of manufacture it offers the minimum amount of skin friction as the water passes through it and furthermore the use of this form simplifies other of the details used in connection with its operation.

10 The outer end 7 of the scoop 6 is also circular in cross section and is formed substantially at right angles to the ring portion 8 and is turned toward the front 9 of the tender, it being assumed that water will 15 be taken up only when the locomotive and tender are traveling ahead.

15 The front 10 of the scoop is, of course, open so that the water in the track tank 20 may have full access thereto when the outer end 7 is partly submerged.

25 By cutting away the lower portion of the outer end 7 of the scoop, the upper portion 11 of the same is made to extend slightly more toward the front than the lower portion 12, by which construction the upper portion forms a hood or shield and there will consequently be more tendency for the water to rush up the scoop and less tendency 30 to splash.

35 At 13 I provide an opening in the top of the tender tank and embracing this opening and secured to the top plate 14 of the tender is a flanged collar 15, the opening through the same being made on the same circular arc as the ring portion of the scoop 6, the scoop passing loosely through this collar into the tender tank, the collar 15 serving as a guide for the said scoop.

40 When the outer end of the scoop is projected into the track tank the inner end 16 of the scoop is in the upper part of the tender tank, just below the bottom of the collar 15. When the scoop is withdrawn 45 from the track tank, as before stated it travels in the path of a circular arc about a center 17, the portion 8 of the scoop traveling back through the flanged collar 15, and telescoping into the water space of the 50 tender tank, the positions of the ends 16 and 7 when so withdrawn being indicated in dotted lines.

55 Thus it will be seen that the scoop when not in use occupies a convenient, yet out-of-the-way position from which it may be readily projected again into the track tank.

60 It will also be seen that the peculiar path of the end 7 of the scoop when entering the track tank is very desirable in that the one movement projects the same both outwardly and laterally and hence greatly simplifies the machinery necessary for its operation, which mechanism will now be described.

65 Affixed to the under side of the scoop is a portion of a circular internal gear rack 18

which is concentric with the center 17. This gear rack preferably passes through a suitable opening 19 in the collar 15 and acts as a key in the same to prevent the scoop revolving axially in the said collar. 70

Meshing with the teeth of the rack 18 is a toothed gear wheel 20 which is secured to a shaft 21, which shaft is journaled in bearings, 22, 23, 24 and 25 secured to the top plate 14 of the tender tank. The shaft 21 75 extends forward to the front end or platform of the tender and secured to it at this end is a gear wheel 26 which co-operates with a similar gear wheel 27 which is secured to a short countershaft 28. This 80 countershaft is journaled in any suitable bearing, as 29, and further secured to the shaft 28 or to the gear wheel 27 is a hand wheel 30 which is within easy reach of the attendant on the platform of the locomotive tender.

85 This gear mechanism forms a gear train which may be of any approved form so that the operation of the hand wheel 30 by an attendant will, by means of the gear rack 90 18, project the scoop into the water or withdraw it therefrom, depending upon the direction of rotation of the hand wheel 30.

95 While ordinarily the overbalanced weight of the scoop about the center 17 will, when the scoop is fully withdrawn, prevent the reverse movement of the scoop until assisted by the operator, yet I provide a lock 31 in order to avoid any possibility of the scoop being run out by the jar of 100 the tender and projecting beyond the clearance line when not running in the vicinity of a track tank.

105 In the use of my scoop it is necessary that means be provided for supporting the weight of the same and the water therein when the scoop is projected and in service. To perform this function I provide along the track tank 3 a runway rail 67 which is secured to the track tank in any convenient 110 manner. Secured to the scoop 6 and adapted to co-operate with the runway rail 67 is a runway shoe 67^a and when the scoop 6 is projected, this runway rail is adapted to carry the load of the scoop, the shoe 67^a 115 being adapted to minimize the friction between the parts in running. The scoop mechanism is so constructed that the weight will come as just stated and the rocking of the tender will not effect the depth of 120 the scoop in the water, in as much as the shoe on the rail will always determine this, the scoop 6 being made to vibrate with reference to the tender, and the various parts being constructed to admit of this. The 125

126 splash of the water serves as a water lubricant for the parts in contact. At 76 I provide means of any approved form for throwing the rack 18 out of gear when the scoop is riding on the rail 67. 130

- At the ends of the track tank the rail 67 may be alternately elevated and depressed as shown at 69 and 70 to carry the end of the scoop up over the end of the track tank 5 in case the attendant projects it too soon or fails to withdraw it before reaching the end of the track tank. But I show also another and the more preferable way of accomplishing this in the same figure (Fig. 5), where 10 it will be seen that at 71 I have depressed the track slightly where it runs alongside of the track tank, the height of the track tank being made suitable for the depressed level of the track. When the tender approaches along the higher track at 72 which 15 extends slightly within the limits of the track tank, the scoop will be carried clear of the end of the track tank, and the gradual declination of the track at 73 will gradually 20 immerse the end of the scoop. Leaving the tank, the reverse occurs, the scoop gradually leaving the water along the ascending grade 25 74 and when reaching the normal level at 75, which also occurs slightly within the limits of the track tank, the scoop is high 30 enough to clear the end of the track tank. Thus no accident will occur by an ill timed movement of the scoop in the vicinity of a track tank. Also, after thus leaving the 35 track tank the water will drain out of the scoop, making it much easier to withdraw to its position inside the tender tank. In order to provide double safety, in this respect both forms of the feature just described may be used together.
- In order to carry the scoop when it is projected and is not supported by the rail 67 I provide radial braces or struts as follows: 40 Inside the water compartment of the tender tank is a hinged radial brace or strut 32 which is connected at 33 to a bracket 34 on the inner end of the scoop 6, this internal strut being attached to the scoop at a point 45 that will never pass through the collar 15 when the scoop is projected.
- Only one strut 32 is used inside the tender tank, it being located immediately under the scoop 6. However, two or more might as readily be used.
- The lower end of the strut 32 is hinged at 50 35 to the inside of the tender tank side sheet 36. The pintle 37 of this hinge is as near the center 17 as mechanically practical so that there will be very little binding in the 55 strut as it rotates about the pintle 37 with the in-and-out movements of the scoop 6. This strut 32 is provided to support the inner end of the scoop when the scoop is projected as described.
- Attached to the outer face of the tank 60 sheet 36 is a hinge 38 and hinged to the same by means of the horizontal pintle 39 are two external struts 40 and 41 which are likewise radial and are adapted to support the outer end of the scoop when it is 65
- projected and not otherwise supported. The pintle 39, like the pintle 37 is as near the center 17 as is practical, and I wish it to be understood that when I speak of these struts 32, 40 and 41 as being radial, I apply 70 this term to them on the assumption that it will be mechanically possible to locate these pintles coincident with the center 17.
- It would be desirable to have the radial struts 40 and 41 rigid and extend directly 75 out and attach to the scoop 6, but if such were done these struts would strike the side 36 of the tank when the scoop is withdrawn and even if a pocket were made in the side of the tender tank for these struts the strut 80 40 would strike the shaft 21, preventing the complete withdrawal of the scoop.
- In order to avoid this the radial struts 40 and 41 are made in two parts, 40^a and 40^b and 41^a and 41^b, and the two parts are pivotally connected together at 42, a single pintle 85 serving for both struts. The struts 40 and 41 are located one at each side of the scoop 6 and the outer ends 43 and 44 of the portions 40^b and 41^b are slidably and pivotably 90 connected to the sides of the scoop 6, the pins 45 and 46 forming the pivots and the heads of these pins being arranged to slide in the angular guides 47 and 48 provided for the purpose and rigidly secured to the 95 sides of the scoop.
- The parts are so proportioned that when the scoop is fully projected and the weight not carried by the rail 67, as for example, when not in the vicinity of a track tank, 100 the pins 45 and 46 are in the uppermost extremities of the guides or runners 47 and 48 respectively and the weight of the outer portion of the scoop will be carried by these pins and the struts 40 and 41. The parts 105 are furthermore so proportioned that the portions 40^b and 41^b of the radial struts have not unfolded quite enough to reach a position in the same radial line with the portions 40^a and 41^a. By being so arranged 110 it will insure that the two portions of these struts will be properly folded when the scoop is withdrawn, which folding will now be described.
- When the scoop is withdrawn from the 115 track tank by means of the gear rack 18 and the gear train, the struts 40 and 41, instead of revolving as a whole about the pivot 39, will be broken or folded about the point 42, the portions 40^a and 41^a rotating radially 120 until they strike against the side 36 of the tender tank where they will be stopped, and the further travel of the scoop will rotate the portions 40^b and 41^b about the point 42, the pins 45 and 46 at the same time sliding 125 down the runners 47 and 48. By this means the portions 40^b and 41^b of the struts 40 and 41 will be folded back over the corner of the tender tank and over the shaft 21, in which position these parts are shown in 130

dotted lines in Fig. 1. In projecting the scoop, of course, the reverse movements of the parts occur.

When the scoop is fully projected, with 5 the joint 42 in the struts 40 and 41, these struts would not alone be capable of supporting any load and it is necessary that means be provided to prevent the weight from knuckling the parts 40^b and 41^b about 10 the parts 40^a and 41^a. To accomplish this the links 49 and 50 are provided, these links being pivoted at their outer ends on the same trunnion 42 that connects the two portions of the struts 40 and 41. The inner 15 ends of these links pass loosely through guides or eyes 51 and 52 which are affixed to the top of the tender tank and the ends of the links 49 and 50 are enlarged beyond these guides so that the guides form a stop for the links when they have attained their 20 full travel.

Thus the links 49 and 50 serve as tension members to prevent the collapse of the struts 40 and 41 when under load. And at the 25 same time these links do not interfere with the proper action of the struts when being folded back during the operation of withdrawing the scoop. For it will be seen that the links 49 and 50 will freely slide back 30 through the loose fitting guides 51 and 52 and will finally end in the position shown in dotted lines when the scoop is entirely withdrawn.

It is also necessary when the scoop is 35 taking up water that means be supplied for staying or bracing the outer end of the same longitudinally of the tender. While the struts 40 and 41 may be made to serve partially for this, yet I provide additional stays 40 for this purpose which I have made of short pieces of cable or rope, or they might be of any other suitable flexible material.

The outer ends of these cables 53 and 54 are affixed to the opposite sides of the scoop 45 near its outer end at 55 and 56 and the inner ends of the cables are affixed to the side 36 of the tender at 57 and 58, these points being somewhat removed toward the front and rear of the tender respectively from the 50 scoop. The length of these cables is such that the cables come taut when the scoop is fully projected, and on the scoop being withdrawn, the cables bend back over the upper edge of the tender as shown in dotted lines in Fig. 1.

In Fig. 4 I have shown an alternate arrangement of scoop and means for projecting it, also an alternate method of bracing and supporting it.

60 In this alternate device an external gear rack 59 is attached to the upper periphery of the scoop, this gear rack being otherwise similar to the rack 18 already described. A similar collar 60 is attached to the top of the 65 tender, this collar serving in every way the

same as the collar 15 and in addition the bearings for the shaft 61, which shaft replaces shaft 21 in the first arrangement, are secured to this collar instead of to the top of the tender. 70

A gear train similar to that already described is likewise used for moving the scoop, the gear wheel 62 being secured to the shaft 61 and meshing with the rack 59.

By locating the rack 59 on the back of 75 the scoop and shaft 61 as shown I am enabled to make both the internal radial strut 63 and the external radial strut 64 without the joints such as are necessary in the previous arrangement for the external struts. 80 The positions of the various parts when the scoop is fully withdrawn are shown in dotted lines and in order that the strut 64 may pass to the position indicated a pocket 65 is made in the side of the tender tank, the 85 formed or bent plate 66 being provided to form this pocket and complete the side of the tank which must necessarily be cut away. One strut only of 63 and 64 is used in this alternate arrangement, the cables 53 and 54 90 serving as before to stay the scoop laterally.

In order that flying cinders may not enter the water compartment of the tender when the scoop is withdrawn, I provide the pivoted flap 77 which is pivoted to the 95 tender by means of the vertical pindle 78, the metal of the flap extending around the pindle and forming an arm or extension 79. When the scoop is projected the portion 11 thereof strikes the flap 77 and pushes it to 100 the position shown in dotted lines in Fig. 6, the spring 80 holding it in this position until the scoop is withdrawn. On withdrawing the scoop the portion 81 strikes the extension 79 and the flap is swung around to 105 cover the open end 10 of the scoop, the spring 80 now serving to hold the flap against the open end of the scoop. The dotted lines for the end of the scoop in Fig. 6 show the scoop just as it strikes the extension 79 of the flap. 110

In order that water may not be splashed out the open end of the scoop when the same is withdrawn and the tender tank filled I provide the inwardly opening check valve 115 82 in the scoop. This check valve is so disposed that the pindle 83 thereof is substantially vertical when the scoop is projected and horizontal when withdrawn, the swinging check thus being easy to open when projected and falling by gravity against its seat when the scoop is withdrawn. 120

From the description and drawings it will be seen that I have provided a workable device, even in detail, to take up water at 125 slow speeds and to perform the other functions. And while I have thus described the specific form of many of the elements used I do not wish to be limited to their exact form and construction as various changes 130

might be made within the scope of the claims by those skilled in the art without departing from the spirit of my invention.

Having thus described my invention, what

5 I claim is:

1. In a locomotive tender tank feeding apparatus the combination with a locomotive tender provided with a tank, of a track tank placed parallel to the track and at one side thereof, a water scoop movably attached to the tender and adapted to be projected into the said track tank, the said scoop having a tubular portion which is in constant communication with the interior of the tender tank, and means for projecting and withdrawing said scoop in a direction transverse to the line of travel of the tender and coincident with the axis of said tubular portion. 70
- 10 2. In a locomotive tender tank feeding apparatus, the combination with a tender provided with a closed tank having an aperture in its top wall, of a track tank placed parallel to the track and at one side thereof, a water scoop movably attached to the tender and having a tubular portion which always passes through said aperture, and means for projecting and withdrawing said scoop to and from a position in which the 75 scoop to and from a position in which the 80 scooping end may enter the track tank, the path of travel of the said scoop when being so projected and withdrawn being in a direction transverse to the track and coincident with the axis of said tubular portion. 85
- 15 3. In a locomotive tender tank feeding apparatus, the combination with a tender provided with a closed tank having an aperture in its top wall, of a track tank placed parallel to the track and at one side thereof, a water scoop movably attached to the tender and comprising a portion of a tubular ring which always passes in an arcuate path through said aperture, and means for projecting and withdrawing said scoop to and 90 from a position in which the scooping end may enter the track tank, the path of travel of said scoop when being so projected and withdrawn being in a direction transverse to the track and coincident with the arcuate axis of said scoop. 95
- 20 4. In a locomotive tender tank feeder the combination with the locomotive tender of a track tank disposed longitudinally of the track and to the side thereof, a water scoop affixed to the said tender and adapted to be projected into and withdrawn from the said track tank, a runway rail secured to said track tank and disposed longitudinally of the same, and a runway shoe secured to said 100 water scoop and adapted to coöperate with said runway rail when the said water scoop is projected into the said track tank. 105
- 25 5. In a locomotive tender tank feeding apparatus the combination with a locomotive tender provided with a tank, of a track tank of semicircular cross section placed parallel to the track and at one side thereof, a water scoop movably attached to the tender and adapted to be projected into the said track tank, the said scoop having a tubular portion which is in constant communication with the interior of the tender tank, and means for projecting and withdrawing said scoop in a direction transverse to the line of travel of the tender and coincident with the axis of said tubular portion, the said scoop being provided with a cylindrical, longitudinal extension at its outer end of a size suitable for admission within the said track tank. 110
- 30 6. In a locomotive tender tank feeding apparatus, the combination with a tender provided with a closed tank having an aperture in its top wall, of a track tank placed parallel to the track and at one side thereof, a water scoop movably attached to the tender and comprising a portion of a tubular ring which always passes through said aperture, and means for projecting and withdrawing said scoop to and from a position in which the scooping end will be within the track tank, the said scoop traveling in the path of a circular arc in a vertical plane and in a direction transverse to the track and coincident with the axis of said scoop. 115
- 35 7. In a locomotive tender tank feeder, a water scoop comprising a portion of a hollow ring, in combination with the locomotive tender, said water scoop being movably secured to the said tender and adapted to move in the path of a circular arc transversely of said tender, and means for effecting the said movement of the water scoop. 120
- 40 8. In a locomotive tender tank feeder the combination with the locomotive tender of a hollow water scoop, said water scoop comprising a portion of a hollow, cylindrical ring and being hinged to said tender and adapted to swing in the path of a circular arc transversely thereof and co-incident with the arcuate axis of said scoop, and radial struts adapted to support the said water scoop, said radial struts being secured to the water scoop at their outer ends and pivotally secured to said tender at their inner ends, the pivot point being substantially at the center of the circular arc of travel of the said water scoop. 125
- 45 9. In a locomotive tender tank feeder the combination with a locomotive tender having side walls of a hollow water scoop, said water scoop being hinged to said tender and adapted to swing in the path of a circular arc transversely thereof, a radial strut within the water space of said tender and a radial strut external of said water space, said radial struts being adapted to support the water scoop and being secured thereto at their outer ends and pivotally secured to said tender at their inner ends, at points ad- 130

6
jacent each other the pivot points being substantially at the center of the circular arc of travel of the said water scoop, the side wall of the tender being interposed between 5 the mechanical pivots of the respective struts and forming an unbroken water retainer.

10. In a locomotive tender tank feeder the combination with the locomotive tender 10 of a hollow water scoop, said water scoop being hinged to said tender and adapted to swing in the path of a circular arc transversely thereof, a radial strut within the water space of said tender and a radial strut 15 external of said water space, said radial struts being adapted to support the water scoop and being secured thereto at their outer ends and pivotally secured to said tender at their inner ends, the pivot point 20 being substantially at the center of the circular arc of travel of the said water scoop, the said external radial strut having a pivoted joint intermediate its length whereby the outer portion thereof may be 25 folded inwardly over the top of the tender.

11. In a locomotive tender tank feeder the combination with the locomotive tender of a hollow water scoop, said water scoop being hinged to said tender and adapted to swing 30 in the path of a circular arc transversely thereof, a radial strut within the water space of said tender, a radial strut external of said water space, said radial struts being adapted to support the water scoop and 35 being secured thereto at their outer ends and pivotally secured to said tender at their inner ends, the pivot point being substantially at the center of the circular arc of travel of the said water scoop, the said external radial strut having a pivoted joint intermediate its length whereby the outer portion thereof may be folded inwardly 40 over the top of the tender, and a link between the tender and the joint in said radial 45 strut, said link being adapted to prevent the outward folding of the radial strut.

12. In a locomotive tender tank feeder the combination with the locomotive tender of a water scoop adapted to be projected laterally therefrom and a flexible connection 50 between said tender and the outer end of said water scoop, said flexible connection forming a stay for said water scoop longitudinally of the said tender when the said scoop 55 is projected, said flexible connection being secured to the side of the said tender at a point in advance of the said scoop and being

formed and disposed in such manner as to be drawn taut upon the projection of the said scoop and to collapse and retreat with 60 the retreat of the same.

13. In a locomotive tender tank feeder, the combination with a railway track of a locomotive tender adapted for use on the same, a water retaining track tank adjacent the track and extending longitudinally thereof, the same having end heads which extend above the water level therein, a water scoop affixed to said tender and adapted to be projected nearly but not fully into 65 the scooping relationship with the said track tank and the water therein, the said track being depressed within the limits of the said track tank and relative thereto below its normal level in such manner as to bodily 70 lower the entire tender to a level wherein the said scoop will be lowered therewith into completed scooping relationship with the said track tank and the water therein, the normal level of the said track prevailing at 75 the ends of the said track tank and the projected position of the said scoop being such that at the normal track level the end of the scoop will pass over the end heads of the track tank, together with means for projecting and withdrawing the said scoop. 80

14. In a locomotive tender tank feeder the combination with the locomotive tender of a track tank disposed longitudinally of the track, a water scoop affixed to said tender 90 and adapted to be projected into and withdrawn from the said track tank, a runway rail disposed longitudinally of the said track tank and a runway shoe secured to the said scoop and adapted to coöperate with 95 the said runway rail when the scoop is projected into the said track tank, the vertical relation of the scoop and the track tank being thereby regulated.

15. In a locomotive tender tank feeder the combination with the locomotive tender of a movable water scoop having its outer end open, and a movable flap mounted on said tender and adapted to close the open end of the said scoop, the said flap being automatically operated by the movements of the said scoop. 100

In testimony whereof I affix my signature in presence of two witnesses.

JOHN A. PILCHER.
